QUINONYL SULPHONAMIDES IN COLOR
COMPOSITIONS

Roy Herman Kienle and Chester Albert Amick,
Bound Brook, N. J., assignors to American
Cyanamid Company, New York, N. Y., a corpo-
ration of Maine

No Drawing. Application July 1, 1943,
Serial No. 493,133

9 Claims. (Cl. 8—70)

This invention relates to a new type of dyeing and printing assistant, dye compositions containing these assistants and products printed therefrom.

Use of printing-color pastes containing dyes, particularly in printing operations using vat dyes, is sufficiently well known so that the procedure has become almost standardized. The actual color source may be either a dye paste or a dye powder. In addition to the real color, a dye paste usually contains agents to prevent drying-out, settling and/or freezing. Dye powders, not being subject to these difficulties, do not require these agents but they usually contain agents or are so processed as to promote dispersibility.

In either case, the dye paste or dye powder must be admixed with suitable thickener, usually a gum dispersion, to form a printing-color paste which is suitable for application. In the case of vat dyes, it is also necessary to add a reducing agent and usually an alkali. Because the color yield from printing-color pastes often decreases rapidly as the paste ages after being made up, these printing-color pastes are usually prepared by the fabric finishers just before they are to be used.

The printing-color pastes, however compounded, are then applied to textile, paper or other fabric materials for decorative or protective purposes. The printed pieces are dried, aged in a steam ager, treated with an oxidizing agent, rinsed and finally dried. Usually in processing textiles, the printed fabric also is soaped at or near the boil with about a 0.1% soap solution and again rinsed before the final drying operation.

In making up and applying printing-color pastes it has been found that a material suitable for use as a printing assistant is of advantage in obtaining maximum color yield. The exact way in which these materials act to produce an improved color yield in printing is not entirely understood. It is with these printing aids or assistants that the present invention is particularly concerned.

Although printing aids are desirable in the printing-color pastes, the exact point at which they are added may vary. Dye pastes may contain printing aids as one of their components and printing-color pastes made therefrom will obviously contain the printing assistant. Where a printing assistant is not present in the dye paste, it may be added at the time of making up the printing-color paste.

It is preferable, however, that the printing assistant be incorporated in the actual dye paste.

Their addition at the proper point in the manufacture of the paste is not only easier, but in addition they are thus generally more uniformly dispersed throughout a printing-color paste made therefrom. As a result, the printing assistants usually operate more effectively when the printing-color paste is finally applied to the fabric.

It is only relatively recently that dye powders suitable for use in making up printing-color pastes have been available. Most of the printing aids previously used in dye pastes, being either liquid in form or extremely hygroscopic, can not be used with dye powders, the latter being necessarily limited to the use of dry solids. Nevertheless, it is desirable that printing assistants be incorporated in the powders at the time of manufacture for the same reasons which apply in the case of dye pastes.

20 Dye pastes containing various liquid printing assistants have been made. Among the liquid materials used are the alkylol amines, for example, triethanol amine; and/or polyhydric alcohols such as glycerine, glycol, diethylene and the like. 25 Various derivatives therefrom also have been tried. If a printing aid is to be incorporated in a dye powder, a solid printing aid is necessary. Examples of such solids which have been used in the past include the hydrochlorides of alkylol amines, anthraquinone, silver salt (sodium anthraquinone beta-sulphonate) and certain metal salts such as those of cobalt and iron.

Unfortunately, most of these printing aids previously used are not as satisfactory as may be desired. Many of them will not in all cases produce the intensification of color for which they were intended. Others, such as the polyhydric alcohols, cause deterioration of the printing-color pastes so that marked variations in the strength of prints therefrom are observable even after the printing-color paste has been allowed to stand for only a relatively short time. Many of them are satisfactory with some colors but have an adverse effect on others, even to the extent of visibly altering the shade. None of them are suitable without modification for use both in paste and powder compositions.

One of the types of compounds which in the past has been proposed for this purpose is the arylsulphaminoanthraquinones. Unfortunately, the use of these compounds has several disadvantages from a practical point of view. It is extremely difficult to make a suitable formulation with these products. Unless they are in a very finely divided condition, prints from pastes con-

taining these materials are usually found to be badly specked. When in this finely divided state it is substantially impossible to wet them out uniformly in aqueous media. The resultant lack of homogeneity causes trouble both in making up color compositions and in applying them to fabrics. Particularly is this noticeable if it is attempted to make use of dyes and dye compositions in powdered form.

There remains, therefore, a demand for suitable printing assistants which will produce a satisfactory color intensification, may be readily compounded and will not cause deterioration of the dyeing or printing composition on standing. Preferably also, the assistants should be useful both with dye pastes and dye powders and in addition should be readily available or cheaply and easily prepared. It is, therefore, the object of the present invention to provide a new type of printing assistant which possesses these desirable properties.

In general the objects of the present invention are accomplished by using as a printing assistant a quinonyl sulphonamide or a derivative thereof represented by the general formula

in which Q represents the residue of a quinone such as alpha- or beta-anthraquinone and beta-naphthoquinone; R₁ and R₂ represent hydrogen or alkyl, aryl or alkaryl radicals and x may be 1 or 2. Typical of the sulphonamides of the present invention are the mono- and disulphonanilides of beta-anthraquinone which may be represented by the formulae:

Use of these compounds was found to have several important advantages. They are completely free from the wetting out problems noted for example in the case of the arylsulphamino-anthraquinones. Being either soluble or readily dispersible in the usual components of dye and printing pastes, they are readily compounded therein. In addition to overcoming difficulties in this respect, they were found in most cases to produce appreciably better color yields. Further, being dry, solid materials, they are particularly well suited for use in dye powder formulations.

So far as the present invention is concerned the assistants may be added to the printing-color pastes at any point. They may be incorporated into the thickener; into the dye pastes or powders or may be blended directly into the printing-color paste. However, as pointed out above, it is preferable that they be incorporated in the dye paste or powder during manufacture. Similarly, if so desired they may be used in conjunction with other printing assistants.

In preparing the sulphonamides used as printing assistants according to the present invention, the quinonyl radical represented by Q in the generic formula is ordinarily limited to the alpha- and beta-anthraquinones and beta-naphthoquinone. The corresponding derivatives of 1,4-naphthoquinone do not appear to be capable of being isolated, if they form. In the case of beta-naphthoquinone, x in the generic formula is ordinarily one since the disulphonamides of beta-naphthoquinone are impractical to form.

In using the compounds of the present invention as printing assistants it is not necessary that the application be limited to the use of sulphonamides in which R₁ and R₂ both represent hydrogen. Such compounds, however, do make excellent printing assistants. Nor is it necessary that R₁ and R₂ both represent similar groups. In the present case, substituted-derivatives, for example, in which either R₁ or R₂ is hydrogen and the other is an alkyl radical, as in the alpha- or beta-anthraquinone-sulphonethylide; an aryl radical, as in an alpha- or beta-anthraquinonesulphon-anilid; a sulphonated-aryl group, as in an alpha- or beta-anthraquinone-sulphonsulphanilide or an alkaryl radical as in an alpha- or beta-anthraquinone-sulphon-toluidide or sulphon-xylidide were prepared.

These compounds were found to serve excellently as printing assistants with substantially any of the vat dyes. Particularly was this true in the case of the thio-indigos. Perhaps the most noticeable improvement was found on adding the sulphon-sulphanilids and sulphon-toluidides so that these compounds are perhaps preferable although the invention is not necessarily meant to be so limited.

While the dye and printing paste compositions of the present invention are not limited to the use of any particular dyes or dye forms, they are especially suitable for use with vat-dyes in either paste or powder form. Particularly good results may be obtained using the vat-dye powders of high-autodispersibility set forth in Crossley et al., United States Reissue Patent 21,402, reissued March 19, 1940. By combining the color materials of that patent into printing-paste compositions containing the printing assistants of the present invention, the full advantages of both may be gained with a resultant simplicity in use and excellence of shade and sharpness of color. Printing pastes made in this way have the particular advantage that the dyes remain in a highly dispersed state because they are taken up as individual particles rather than as dispersion of particle aggregates. In the present specification and claims, where highly-dispersed dyes are referred to, reference to pastes in which the dye is so dispersed is intended.

The invention will be more fully set forth in connection with the following examples which are intended to be illustrative only and not by way of limitations. All parts are by weight unless otherwise noted.

In the succeeding examples, test prints were made on two different fabrics. When rayon is referred to, a titanium-dioxide-pigmented, all viscose-rayon flat crepe was used. The cotton fabric referred to is an 80 x 80 bleached unmercerized, cotton print-cloth. Ageing of the prints was carried out in a steam ager which was constructed in such a manner that controlled temperatures could be used. The temperature range normally used was 100°-105° C. Those ageing referred to as plant or hot ageing were carried

out in the temperature range of about 106°-110° C. In the case of the cotton prints ageing periods of 3 minutes, 5 minutes or both were used. On rayon, ageing periods of 5 and 10 minutes or both were used. The shortest period which gives a satisfactory ageing is preferable.

Example 1

A paste was prepared by slurring 2,000 parts of 177 British gum (Stein Hall) in 5,000 parts of water and the mixture was heated with continuous stirring until the temperature reached about 185° F. Heating was continued for about 1½ hours after which 450 parts of powdered potassium carbonate and 450 parts of powdered sodium carbonate were added and the mixture stirred until the carbonates dissolved. Heating was discontinued but stirring was continued until the temperature reached approximately 150° F. at which time 700 parts of sodium sulphoxylate were dissolved therein, 600 parts of glycerine were added and the paste bulked to about 10,000 parts. Stirring was continued until the paste cooled to room temperature. In the succeeding examples this paste is referred to as thickener A.

Example 2

2,100 parts of British gum, 200 parts of tapioca flour and 500 parts of corn starch were added to 2,500 parts of water and heated over a steam bath for approximately 1½ hours after the temperature reached 185° F. The source of heat was then removed but stirring was continued until the temperature decreased to 130° F. at which time 2,100 parts of potassium carbonate which had been previously dissolved in hot water was added to the cooked gum. 1,100 parts of sodium formaldehyde sulphoxylate were added to the common mixture at a temperature of about 150° F. Subsequently, 1,400 parts of glycerine were added and after thorough stirring the whole was bulked to about 10,000 parts. The mixture was cooled and stirred continuously until the mass reached room temperature. In the succeeding examples this mixture is referred to as thickener B.

Example 3

720 parts of B-2 British gum and 720 parts of KAC-4 gum (Stein Hall) were added to 5,600 parts of water and heated over a steam bath for approximately 1½ hours after the temperature reached 185°-190° F. The source of heat was then removed but stirring was continued until the temperature decreased to 120° F. at which time 1,200 parts of potassium carbonate which had been previously dissolved in 1,000 parts of water was added to the cooked gum. 1,560 parts of sodium sulphoxylate formaldehyde were dissolved in 1,500 parts of water at a temperature of about 140° F. and added to the common mixture with stirring until the whole was thoroughly mixed. Finally, 360 parts of glycerine were added and after thorough stirring the whole was bulked to 12,000 parts. In the succeeding examples this mixture is referred to as thickener C.

Example 4

10 parts of a Dark Blue BO dispersed powder, prepared according to United States Reissue Patent 21,402 and containing approximately 3.7 parts of real dye, were dry blended with 0.3 parts of anthraquinone-beta-sulphonanilid, after which 89.7 parts of thickener C were added and thoroughly mixed. A second 10 parts of Dark Blue

BO dispersed powder was blended with 90 parts of the thickener C only. Each of these pastes were printed on cotton. The printed pieces were air dried, aged, oxidized after the ageing, soaped for 5 minutes in a 1% soap solution at the boil and ironed dry. Prints obtained from the paste containing the anthraquinone-beta-sulphonanilid were much stronger than those from the paste containing no assistant.

Example 5

The procedure of Example 4 was duplicated except that Golden Orange G (C. I.-1096) containing about 1.9 parts of real dye was substituted for the Dark Blue BO and the prints were made on rayon. Prints from the paste containing the anthraquinone-beta-sulphonanilid were stronger and brighter than those made from the paste which contained no assistant.

Example 6

A sample of wet presscake of Vat Orange R (C. I.-1217) was dispersed with the sodium salt of disulfo-dinaphthylmethane, and adjusted with water to contain 12% real dye. To 10 parts of this mixture was added 0.3 parts of beta-anthraquinonyl-sulphonanilid and 90 parts of thickener C. A duplicate sample was also prepared except that no anthraquinone-beta-sulphonanilid was added. Each of these pastes were tested on rayon and cotton. The prints from the paste containing the anthraquinone-beta-sulphonanilid were much stronger and brighter than those obtained from the paste which contained no assistant.

Example 7

Example 6 was again repeated, substituting beta-anthraquinonyl-sulphonethylide for the sulphonanilid. Again the prints from the paste containing the printing assistant were definitely superior to those from the blank.

Example 8

100 parts of a concentrated Vat Orange R powder prepared according to United States Reissue Patent 21,402 were ball milled for 3 hours with 3.7 parts of anthraquinone-beta-sulphonanilid powder. To this mixture were added 35.3 parts of Cerelose and the milling was continued for 18 hours. 10 parts of the above product which contained about 2.4 parts of real dye were then mixed with 90 parts of thickener A. A second 100 parts of the concentrated Orange R powder were also ball milled with 39 parts of Cerelose for 21 hours and mixed with 90 parts of thickener A to make a control paste. Both of these pastes were printed on cotton. The prints from the paste containing the anthraquinone-beta-sulphonanilid gave much stronger and brighter prints than those from the paste containing Cerelose only.

Example 9

The procedure of Example 8 was repeated except that alpha-anthraquinonyl-sulphonanilid was used in place of the beta-derivative. Substantially identical results were obtained.

Example 10

The procedure of Example 8 was followed except that six parts of beta-anthraquinonyl-sulphonanide was used in place of the anthraquinonyl-sulphonanilid and the Cerelose content was

reduced to 33 parts. After milling, the color mixtures were again made into printing color pastes using thickener A. Prints obtained from the paste containing sulphonamide were much stronger than those obtained from the paste containing Cerelose only.

Example 11

The procedure of Example 10 was followed except that the alpha-anthraquinonyl-sulphonamide was used in place of the beta-sulphonamide. Prints obtained from the paste containing the alpha-anthraquinonyl-sulphonamide were substantially the same as those from the paste containing the beta-derivative of Example 9.

Example 12

Example 8 was again repeated except that the anthraquinone-beta-sulphonanilid was replaced by beta-anthraquinonyl-sulphon-p-toluidide. After milling 10 parts of this mixture were mixed with 90 parts of thickener B to form a printing paste. 10 parts of the control sample were also mixed with 90 parts of thickener B also. Each of these pastes were printed on rayon. Prints obtained from the pastes containing the beta-anthraquinone-sulphon-p-toluidide were stronger and brighter than the prints obtained from the printing paste containing no printing assistant.

Example 13

The procedure of Example 12 was followed exactly except that the beta-anthraquinonyl-sulphon-p-toluidide was replaced by alpha-anthraquinonyl derivative. Again it was found that interchanging the alpha- and beta-anthraquinones gave substantially the same color yields on a basis of true color content in the printing pastes.

Example 14

Again the procedure of Example 12 was followed, using beta-anthraquinonyl sulphonamide-benzene sulphonic acid as the printing assistant. Again, marked improvement in the color yield from paste containing the assistant was obtained.

Example 15

900 parts of Vat Pink FF presscake were deflocculated with the sodium salt of disulphodinaphthylmethane, then passed through a Mikro colloid mill to give a smooth, uniform suspension. This product was called "Vat Pink FF deflocculated press cake." After determining the dye content of this material, a weighed quantity was entered in a ball mill. To this mass enough water was added to reduce the dye content to approximately 15% and the mix was ground for 24 hours. This 15% Pink FF water paste was called "the blank." A second quantity of Vat Pink FF deflocculated press cake from the same batch containing approximately 30 parts of pure dye was ground in a ball mill with 6 parts of beta-anthraquinonyl sulphonamide and enough water to reduce the dye content to approximately 15% for approximately 24 hours. Both samples were then analyzed for extracted solids, and the efficiency factor was determined. The value of the blank was arbitrarily fixed at one. Both samples were printed on cotton and the color values of the prints determined spectrometrically and the ratio of color value containing the printing assistant over that of the blank was determined also. The efficiency factor was 1.47 when the anthraquinone-beta-sulphonamide was used as

a printing assistant, showing an improvement of approximately 47% over prints from the paste containing water only.

Example 16

The procedure of Example 15 was repeated exactly except that the beta-anthraquinonyl sulphonamide was replaced by beta-anthraquinonyl sulphon-p-toluidide. The "efficiency factor" was 1.4 showing that the print from the paste containing the anthraquinone beta-sulphon-p-toluidide was approximately 40% stronger than the print from the paste containing water only.

Example 17

15 The printing assistants of Examples 8 and 10 were again tested using thickener B. Again the prints obtained from the pastes containing the printing assistants were stronger and brighter than those obtained from the pastes containing 20 Cerelose only indicating that the improved effect produced by the anthraquinonyl-sulphon-derivatives is not due to a particular thickener used in making up the printing paste.

We claim:

1. A color composition comprising a vat dye and a quinonyl sulphonamide having the general formula

in which Q represents a quinonyl radical selected from the group consisting of the beta-naphthoquinonyl and the anthraquinonyl radicals, R₁ represents a radical selected from the group consisting of hydrogen and the alkyl, aryl and alkaryl radicals and x is a small whole number selected from the group consisting of 1 and 2.

2. A dye powder composition comprising a vat dye and a powdered quinonyl sulphonamide having the general formula

in which Q represents a quinonyl radical selected from the group consisting of the beta-naphthoquinonyl and the anthraquinonyl radicals, R₁ represents a radical selected from the group consisting of hydrogen and the alkyl, aryl and alkaryl radicals and x is a small whole number selected from the group consisting of 1 and 2.

3. A dye powder composition comprising a vat dye powder of high autodispersability and a powdered quinonyl sulphonamide derivative having the general formula

in which Q represents a quinonyl radical selected from the group consisting of the beta-naphthoquinonyl and the anthraquinonyl radicals, R₁ represents a radical selected from the group consisting of hydrogen and the alkyl, aryl and alkaryl radicals and x is a small whole number selected from the group consisting of 1 and 2.

4. A color composition according to claim 1 in which Q represents the beta-naphthoquinonyl group.

5. A color composition according to claim 1 in which Q represents an anthraquinonyl group.

6. A printing paste composition comprising a

vat dye, a thickener and a quinonyl sulphonamide having the general formula

in which Q represents a quinonyl radical selected from the group consisting of the beta-naphthoquinonyl and anthraquinonyl radicals, R₁ represents a radical selected from the group consisting of hydrogen and the alkyl, aryl and alkaryl radicals and x is a small whole number selected from the group consisting of 1 and 2.

7. A printing paste composition comprising a highly-dispersed vat dye, a thickener and a quinonyl sulphonamide having the general formula

in which Q represents a quinonyl radical selected from the group consisting of the beta-naphthoquinonyl and anthraquinonyl radicals, R₁ represents a radical selected from the group consisting of hydrogen and the alkyl, aryl and alkaryl radicals and x is a small whole number selected from the group consisting of 1 and 2, obtainable by compounding a colloidized vat dye powder of high autodispersibility and the quinonyl sulphonamide with the thickener.

8. A method of printing with vat colors which

comprises printing a fabric with a printing paste composition comprising a vat dye, a thickener and a quinonyl sulphonamide having the general formula

in which Q represents a quinonyl radical selected from the group consisting of the beta-naphthoquinonyl and the anthraquinonyl radicals, R₁ represents a radical selected from the group consisting of hydrogen and the alkyl, aryl and alkaryl radicals and x is a small whole number selected from the group consisting of 1 and 2.

9. An article of manufacture comprising a fabric printed with a composition comprising a vat dye and a quinonyl sulphonamide having the general formula

25 in which Q represents a quinonyl radical selected from the group consisting of the beta-naphthoquinonyl and the anthraquinonyl radicals, R₁ represents a radical selected from the group consisting of hydrogen and the alkyl, aryl and alkaryl radicals and x is a small whole number selected from the group consisting of 1 and 2.
